UNITED STATES PATENT OFFICE.

JACOB S. SHERMAN, OF CHICAGO, ILLINOIS, ASSIGNOR TO UNIVERSAL LAMP COMPANY, OF CHICAGO, ILLINOIS, A CORPORATION OF ILLINOIS.

DESIGN FOR A SMOKER'S ASH RECEIVER.

Application filed March 5, 1926. Serial No. 16,797. Term of patent 14 years.

To all whom it may concern:

Be it known that I, JACOB S. SHERMAN, a citizen of the United States, residing at Chicago, in the county of Cook and State of Illinois, have invented a new, original, and ornamental Design for Smoker's Ash Receiver, of which the following is a specification, reference being had to the accompanying drawing, forming a part hereof.

In the illustration,
Fig. 1 is a perspective view; and
Fig. 2 is a side elevational view of the article, showing my new design.

What I claim is:
The ornamental design for a smoker's ash receiver, substantially as shown.

JACOB S. SHERMAN.
